UNITED STATES PATENT OFFICE.

ARCHIBALD DOUGLAS POWELL, OF BRAINTREE, ENGLAND.

LIFTING JACK.

1,422,781.

Specification of Letters Patent. Patented July 11, 1922.

Application filed October 26, 1920. Serial No. 419,597.

To all whom it may concern:

Be it known that I, ARCHIBALD DOUGLAS POWELL, subject of His Majesty the King of England, and resident of Braintree, in the 5 county of Essex and Kingdom of England, have invented certain new and useful Improvements in or Relating to Lifting Jacks (for which I have filed an application in 10 England Dec. 10, 1919, No. 30,987), of which the following is a specification.

This invention relates to improvements in lifting jacks of the type in which the lifting operation is accomplished mechanically and the lowering is controlled by fluid pressure. 15 The object of this invention is to provide an improved method of operating a lifting jack of the above type.

With this object in view the invention is characterized in that means are provided 20 whereby the lowering operation cannot be effected before the manually operated pawl is disengaged.

The invention also consists in providing means, adapted to be actuated by the 25 mechanical means, for effecting the lowering of the jack, and means to prevent the jack being lowered inadvertently.

The invention will now be described with 30 reference to the accompanying drawings, in which:—

Figure 1 is a sectional elevation of one form of lifting jack constructed according to this invention;

Figure 2 is a plan thereof;

Fig. 3 is a side view;

Fig. 4 is a similar view to Figure 1, showing the jack in its lowering position;

Figure 5 is a sectional elevation of a modified form of lifting jack;

Figure 6 is a plan thereof;

Figure 7 is a side view;

Figure 8 is a similar view to Figure 5 showing the jack in its lowering position;

Figure 9 is a sectional elevation of a further modified construction, and

Figure 10 is a similar view showing the jack in its lowering position.

As shown more particularly in Figures 1 to 4, the base or pedestal 1 of the lifting jack 50 comprises a container 2 for fluid such as oil and a housing or sustaining cylinder 3 in which is slidably mounted a piston 4 forming part of a rack or toothed spindle 5 which supports a crutch 6 which is mounted on another spindle 7 preferably slidably and adjustably mounted in the before mentioned

piston spindle 5 in the usual manner. The pedestal 1 is slotted at 8 for the reception of a pawl 9 which is adapted to engage with the rack teeth 10 formed on the spindle 5. The 60 pawl 9 is mounted in a lever or handle carrier 11 which is pivoted at 12 to the pedestal 1. A suitable slot 13 is formed in the carrier 11 for the reception of an operating handle or lever 14. The inner end of this lever 14 is adapted to engage, when in normal or operative position for lifting, against a spring 15 to hold the pawl 9 in engagement with the rack teeth 10. The pawl 9 which is suitably weighted at 16 is normally held in engagement with the rack teeth 10 by its abutment against the upper flange 17 of the pedestal 1 but upon the partial withdrawal of the lever 14 and the further lowering thereof the pawl 9 will be disengaged to effect the lowering 70 of the jack. The pivoted carrier 11 is formed with a cam or the like 18 which is adapted to engage with a plunger 19 which is kept in its normal position by a spring 20. The lower end of the plunger 19 is adapted to engage with a ball or other form of valve 21 which is kept in its normal or closed position by a spring 22. This valve 21 is adapted to automatically control the flow of fluid from the container 2 into the housing 3 when the 80 jack is raised.

In operation and when it is desired to raise the jack the lever 14 is inserted in the slot 13 and moved up and down in the usual manner to operate the pawl 9 and effect the 90 raising of the spindle 5. The fluid from the container 2 will be drawn into the housing 3 through the automatic valve 21 and thereby prevent the lowering of the jack. When the lever 14 is lowered to the position shown in 95 Figure 1, the pawl strikes the flange 17 and prevents the cam 18 from engaging the plunger 19 and the inadvertent opening of the valve 21. When it is desired to lower the jack the lever 14 is partially withdrawn from its socket and away from the spring 15 of the pawl 9. Upon further downward movement of the lever 14, after the pawl 9 is allowed to fall out of engagement with the rack by its weighted projection 16, the cam shaped projection 18 will engage the plunger 19 to open the valve 21 and allow the fluid to flow back to the container 2 and steadily lower the jack.

In a modified construction as shown in 110 Figures 5 to 8 the rack teeth 10 on the spindle 5 are engaged by a pinion wheel 23

which is mounted on a shaft 24 and secured to a ratchet wheel 25. About this ratchet wheel 25 is mounted for oscillation an operating lever carrier 26 which is formed 5 with a slot 13 for the reception of the lever 14 which in this case is angularly shaped at its end to engage with the ratchet teeth of the wheel 25. The lever 14 is formed or 10 provided with a pin or projection 27 which is adapted to engage with a lug 28 on the pinion housing of the pedestal 1 and thus prevent the cam shaped projection 18 from 15 engaging with the plunger 19 and the inadvertent opening of the valve 21. Suitable co-operating stops 29 are provided on the carrier 26 and pedestal 1 to limit the upward movement of the lever 14.

The lifting operation is performed in the ordinary manner by the up and down movement of the lever 14 and the jack will be 20 retained in its raised position by the fluid which passes, through the medium of the valve 21, from the container 2 into the housing 3. When it is desired to lower the jack 25 the lever 14 is partially withdrawn and the pin 27 thereon is moved along a suitable slot cut in the side of the carrier 26 so as to be out of engagement with the stop 28. The lever 14 can now be lowered to open the 30 valve 21 through the medium of the cam 18 and plunger 19. The fluid supporting the jack in its raised position will now flow back into the container 2 and the jack will be lowered.

35 In a further modified construction, as shown in Figures 9 and 10 a spring pressed pawl 30 which is adapted to actuate the ratchet wheel 25 is mounted in a carrier 31 which is pivoted on the operating lever carrier 26. The rear end of the carrier 31 is formed with a lug or extension 32, which passes through a slot in the carrier 26 and is adapted to be engaged by the lever 14 to hold the pawl in position for co-operating 40 with the ratchet wheel 25. Upon the removal of the lever 14 the pawl 30 will be moved out of its co-operative position with the ratchet wheel 25 by the spring 33. In this construction the automatic non-return 45 valve 21 is opened as before by the pressure of the fluid entering the sustaining cylinder 3 when the jack is raised. When it is desired to lower the jack the lever 14 is inserted in an additional carrier 34 which is pivoted preferably at the other side of the housing. Upon downward movement of the lever 14 the cam projection 18 will engage 50 the plunger 19 which is formed with a transverse port 35 and adapted to act as a piston valve and thus open communication between the sustaining cylinder and the container 2. Suitable springs 36 and 37 are provided to 55 keep the carrier 34 and the piston valve 19, respectively, in their normal or inoperative position.

In order to allow fluid to rapidly follow the raising of the jack, it is necessary that the port should be of the maximum size, but it will be obvious that if the release valve was fully opened by its plunger the jack 70 would be lowered more rapidly than desired. To obviate this provision is made whereby the plunger actuating the release valve restricts the area of the port before the valve is opened, for instance as shown more particularly in Figure 4.

If desired, a non-return valve, as shown in Figures 9 and 10, may be fitted to any of the jacks above described but in any of the cases the lowering will be effected by the 80 manually operated valve.

It will be seen that in the jacks above described there will be no leakage of the oil or other fluid employed to sustain the jacks in their raised position as there is no need 85 to maintain atmospheric pressure during their operation.

What I claim is:—

1. A lifting jack, comprising a base formed for containing fluid and with a spindle housing, a spindle slidable in the housing formed with ratchet teeth and provided with a crutch at the upper end, the base being formed with a passage from the fluid container to the spindle housing, a valve 95 mounted in the passage and closing it to a reverse flow, and means for elevating the spindle, said means also being adapted to operate the valve to permit a reverse flow of fluid. 100

2. A lifting jack, comprising a base formed with a fluid container, a spindle housing and a passage establishing communication therebetween, means operating automatically to prevent a flow through the 105 passage from the housing to the container, a spindle slidable in the housing, and means for sliding the spindle in the housing, said means being adapted to actuate the first-mentioned means to permit a flow of fluid 110 to the container.

3. A lifting jack, comprising a base formed with a fluid container, a spindle housing and a passage establishing communication therebetween, means mounted in the 115 body and controlling the passage permitting a one-way flow of fluid, a spindle slidable in the spindle housing, and operating means adapted to elevate the spindle in one position thereof and in a second position being 120 adapted to actuate said means in the body to permit a back flow of fluid.

4. A lifting jack, comprising a base formed with a fluid container, a spindle housing and a passage establishing communication therebetween, means permitting a 125 one-way flow of fluid in the passage, a spindle slidably mounted in the housing, operating means adapted to elevate the spindle, said operating means being adapted to ac- 130

tuate the means in the passage to permit a reverse flow of fluid, and means for preventing the operation of the first-mentioned means during the operation of the operating 5 means in elevating the spindle.

5. A lifting jack, comprising a base formed with a fluid container, a spindle housing and a passage establishing communication therebetween, a check valve mounted 10 in the passage for normally preventing a flow from the spindle housing to the container, a plunger slidably in the base adapted to operate the check valve to permit a back flow, a spindle slidable in the housing, operating 15 means for elevating the spindle within the limits of one position thereof and in another position thereof adapted to engage the plunger for operating the check valve.

6. A lifting jack, comprising a base 20 formed with a fluid container, a spindle housing and a passage establishing communication therebetween, a check valve mounted in the passage for preventing a reverse flow of fluid, a plunger slidably mounted in the 25 base adapted to engage the check valve, said plunger being formed to control the reverse flow of the fluid, a spindle mounted in the housing, and operating means adapted to 30 elevate the spindle and also adapted to move the plunger and operate the check valve to permit a reverse flow of the fluid.

7. A lifting jack, comprising a base formed with a fluid container, a spindle housing and a passage establishing communication there- 35 between, a check valve for preventing a reverse flow in the passage, a spindle slidable in the housing, a handle carrier pivotally mounted in the housing and having a pawl pivoted thereto adapted to engage teeth 40 formed on the spindle, a handle for operating the handle carrier and the pawl to elevate the spindle, and means operated by the handle carrier for engaging the check valve to permit a reverse flow in the passage.

45 8. A lifting jack, comprising a base formed with a fluid container, a spindle housing and a passage establishing communication therebetween, a check valve mounted in the passage preventing a reverse flow of the fluid, a spindle formed with ratchet teeth 50 slidably mounted in the housing, a handle carrier pivoted in the base having a pawl pivotally mounted thereto for engaging the rack on the spindle for elevating the spindle

in the operation thereof, and means operated 55 by the handle carrier for operating the check valve to permit a reverse flow, said pawl being formed to prevent the operation of the check valve during the engagement of the pawl with the rack.

60 9. A lifting jack, comprising a base formed with a fluid container, a spindle housing and a passage establishing communication there- 65 between, a check valve mounted in the passage preventing a reverse flow therein, a plunger slidably mounted in the base adapted to engage the check valve, a spindle formed with ratchet teeth slidable in the housing, a handle carrier pivoted in the base and having a pawl pivoted thereto adapted to engage 70 the rack for elevating the spindle, a handle adapted for insertion in the handle carrier and adapted to operate the pawl to engage the rack for elevating the spindle in the operation of the handle carrier, said 75 handle carrier being formed with a cam for operating the plunger and check valve to permit a reverse flow in the passage, the operation of the plunger by the handle carrier being prevented while the handle projects the pawl into engagement with the rack.

10. A lifting jack, comprising a base formed with a fluid container, a spindle housing and a passage establishing commun- 85 ication therebetween, a check valve for preventing a reverse flow in the passage, a plunger slidable in the base adapted to engage the check valve, a spindle formed with ratchet teeth slidably mounted in the hous- 90 ing, a handle carrier pivotally mounted in the base having a pawl pivoted thereto adapted to engage the rack and formed with a handle receiving portion, a cam for engaging the plunger, and a handle slidably 95 mounted in the handle receiving portion adapted in one position thereof to project the pawl for operative engagement with the rack for elevating the spindle, and in another position thereof to permit the move- 100 ment of the pawl to an inoperative position and the engagement of the cam with the plunger to operate the check valve to permit a reverse flow.

In testimony whereof I have hereunto 105 signed my name.

ARCHIBALD DOUGLAS POWELL.
